CLAIM

The ornamental design for a water closet, as shown and described.

DESCRIPTION

FIG. 1 is a perspective view of the top, front and right side of a water closet showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is a perspective view of the top, front and right side of a water closet showing our new design of second embodiment;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom view thereof;

FIG. 15 is a perspective view of the top, front and right side of a water closet showing our new design of third embodiment;

FIG. 16 is a front view thereof;

FIG. 17 is a rear view thereof;

FIG. 18 is a left side view thereof;

FIG. 19 is a right side view thereof;

FIG. 20 is a top plan view thereof;

FIG. 21 is a bottom view thereof;

FIG. 22 is a perspective view of the top, front and right side of a water closet showing our new design of fourth embodiment;

FIG. 23 is a front view thereof;

FIG. 24 is a rear view thereof;

FIG. 25 is a left side view thereof;

FIG. 26 is a right side view thereof;

FIG. 27 is a top plan view thereof; and,

FIG. 28 is a bottom view thereof.

The portion of the article in broken lines are shown for illustrative purposes only and from no part of the claimed design.
